UNITED STATES PATENT OFFICE.

GEORGE CANFIELD BLICKENSDERFER AND HERVEY SMITH, OF ERIE, PA.

CONVEYER APPARATUS.

SPECIFICATION forming part of Letters Patent No. 295,478, dated March 18, 1884.

Application filed January 21, 1884. (No model.)

To all whom it may concern:

Be it known that we, GEORGE C. BLICKENSDERFER and HERVEY SMITH, citizens of the United States, residing at Erie, in the county of Erie and State of Pennsylvania, have invented certain new and useful Improvements in Conveyer Apparatus; and we do hereby declare the following to be a full, clear, and exact description of the invention, such as will enable others skilled in the art to which it appertains to make and use the same.

This invention relates to conveyers, such as conveyers of packages and cash in stores and other like uses.

15 The invention consists of improvements in the construction and adjustment of the track, the carriage or car, the means for switching the car off the main track at stations, the means for elevating the car to the track and 20 placing it thereon, and other minor features of construction, as will fully appear hereinafter.

The invention is illustrated in the accompanying drawings as follows:

25 Figure 1 is a perspective view of the tracks and elevator at one of the stations. Fig. 2 is a side elevation, looking in the direction of the tracks. Fig. 3 is an enlarged detail view of parts shown adjacently in Fig. 2. Fig. 4 is a 30 like view to Fig. 2, but shows the car just in the act of switching. Fig. 5 is a like view to Fig. 2, but shows the car just as it is being put on the main track by the shipper. Fig. 6 is a perspective view of the shipper. 35 Fig. 7 is an end view of the shipper, looking from across the track. Fig. 8 is a side view of the running-gear of the car. Figs. 9 and 10 are plan views of the track at corners, Fig. 9 showing a turn past an inner corner, and Fig. 40 10 showing a turn around an outer corner. Fig. 11 is a side view of the iron R, seen in Fig. 9. Fig. 12 is a perspective of the same iron.

45 The track used is a taut wire set at an angle, so as to form an inclined way. There are two tracks, A and B, of which A is used for the car when going to the central station or cashier's desk, and B for the car when going to the way points or stations. Above we have 50 spoken of the track A as the "main track," as

it leads to the central station or cashier's desk, and so we may call the track B the "return-track," as it leads from the cashier's desk or station to the several salesmen's stations along its route, and by it the cars are returned to 55 the salesmen. When a car is put onto the main track at any station, it runs directly through to the central or cashier's station, so there are no switches on that track; but the track B is provided with a switch or side track 60 at each salesman's post or station to receive the car. These switches or side tracks are marked C in the drawings, and they act automatically to receive the car destined for them. Tracks for this purpose formed of a 65 wire drawn taut or of rods of iron are common; and our invention, in so far as the tracks are concerned, consists in the devices employed for making curves or turns around or past corners, and in the manner of adjusting the 70 side tracks with relation to the direct track, so as to automatically receive the car.

The devices used for carrying the track around curves are shown in Figs. 9, 10, 11, and 12. Figs. 9 and 10 show two curves, that 75 in Fig. 9 being within the angle, and the one in Fig. 10 being around the outside of an angle. The one in Fig. 9 is such as the track would make which runs around a room next to the wall, and the one in Fig. 10 is such as 80 the track would make which runs around a set of counters set in the middle of a room. In each the track-wire is marked A, and the curve is marked A'. (Of course, it will be understood that the track B will be erected at 85 corners in the same manner.) It will be seen that the curved part of the track is another or separate piece of material from the main track A. The main wire A passes the corner at an angle, and in such a manner as to enable slack 90 to be taken up, if required, and the curve-track A' is so supported with relation to the track A as to extend the real track in a proper curve around the corner. In Fig. 9 the wire A is supported at the corner by a hook, S, (or it 95 may be an eyebolt,) which passes through a staple-iron, and is made adjustable by a nut for the purpose of taking up slack in the wire A. On the wire A, at the points from which the curve is to diverge, are placed frog-irons 100

R R, (seen in detail in Figs. 11 and 12,) which deflect the main wire A down and up again, and also form a bearing for the curve-piece A', so as to bring its ends in direct line with the 5 main line A. The drop or depression in the main line allows the ends of the curve-piece A' to lie in the plane of the main line, and thus form an even and continuous track. In the curve shown in Fig. 10 the main wire is supported on arms T, extending from the opposite sides of the angle. These arms are T-shaped at their outer ends and perforated or slotted, so that the main wire A can be diverted from the upper to the lower side of the 10 arms, from whence it extends from one arm to the other, forming the chord of the curve, but below the plane of the track, and the curve-piece is attached to the arms T by its ends, which are so adjusted as to continue the track 15 evenly around the curve. It is not necessary that the main line A pass this corner unbroken, for the lines each way may end at the arms; but in that case there should properly be a cross-binder between the arms similar to 20 the line A, where it passes like a chord to the curve.

The arrangement of the switch or side tracks, C, is clearly shown in Figs. 1, 2, 4, and 5, where it will be seen that they do not 25 connect with the direct line, but are adjusted at a point directly above the direct line (or they may be directly below it) and from thence curve off to one side, in the manner of switch-tracks in railroads. These switches 30 can only be used with cars having a special set of wheels for running on the switches, which are adjusted directly above (or below, if the case so be) the main wheels. These switch-tracks may be so adjusted with relation 35 to the position of the extra wheels on the cars as to engage the tread of those wheels and lift the main wheels off of the direct track, and thus switch the cars onto the siding. In our illustration, however, we show means for un- 40 shipping the main wheels, and thus making the car drop onto its extra wheels on the switch-track. The essential feature of this part of our invention, however, consists in the adjustment of the switch-track in a vertical plane, or sub- 45 stantially so, with the direct track, and the employment of two sets of wheels on the cars, one for the direct track and the other for the switch-track; and therefore whether the switch is adjusted above or below the direct 50 track, or whether the car is picked up from the direct track by the extra wheels running onto the switch, or is made to drop onto the switch, are unessential minor details. If the car is to be picked up by the switch-track, the 55 details of construction to that end would consist wholly in the proper adjustment of the switch-track with relation to the distance the extra wheels are from the direct track, and needs no illustration, as there would be no 60 special appliances, so we have illustrated the means for switching the car by the other meth-

od—viz., that of unshipping the main wheels and allowing the car to drop with its extra wheels onto the switch-track. This construction is clearly seen in Figs. 2, 3, 4, and 8. 70

M is the car, which, as shown, is a wicker-basket with a hinged cover, and the running-gear is attached to the top, so that the car runs along pendent from the track. Baskets of various sizes may be kept at each station, and 75 each may be provided with means for quickly attaching and detaching to and from the running-gear, so that one running-gear may be used for all sizes of baskets.

The running-gear of the car consists of a 80 main upright, M', which is connected with the car M, two cross-arms, N' and O', and the two sets of wheels N and O. The cross-arm O' and wheels O are attached to the upright M' and the cross-arm N', and its wheels N are 85 attached to an upright hinged bar, P. The cross-bar N' is so bent as to curve around the upright M' and thus afford attachment to the bar P and still allow the wheels N to be upon the track. The hinged bar P is pivoted on a 90 stud, m', which extends out from the main upright M'. The lower end of the bar P is curved, as at p', which, when the bar is thrown back, hits upon the under side of the stud m', and serves as a stop to limit the backward 95 movement of the bar P. This position of the parts is seen in Fig. 4, and it is the position assumed when the car is to run on the wheels O. When the car is to run on the wheels N, the bar P is thrown forward and its upper 100 end, p, which is turned at an angle to the main part of the bar and is provided with a hook which passes through an opening in the upright M', and engages with a spring catch-bolt, p², and is thus retained until the catch-bolt is drawn down, when the bar P will be 105 thrown back by the spring p², which is placed between the bar P and the upright M'. Fig. 3 shows the details of this construction clearly. It is now understood that when the wheels N 110 are held in an upright position they will be upon the track, but when thrown back the wheels O will come into use. So this throwing back of the wheels N must only occur when the car is passing the point of a switch-track. There will be cars belonging to each 115 station on the line, and only the cars belonging to a given station should switch off the direct line at that station, and the cars belonging to other stations should pass without 120 being affected. So, then, each switch must act automatically only for the cars belonging at its station. This is accomplished as follows: Extending from the catch-bolt p² out below the track is a pin, p⁵, and on the track 125 at the proper point is a finger, b, which, as the car passes, will draw down the catch-bolt by pressing upon the pin p⁵. Now, if the fingers b are all of different length and are so placed along the line that they will be successively 130 longer, the farther the stations are removed from the central station and the pins p⁵ on

the several cars designed for the several stations are properly adjusted as to distance below the track, then the car designed for the farthest station will not come in contact 5 with any of the fingers *b* at the intermediate stations, and hence will not be switched until it reaches its station. In other words, when a car reaches a station with a finger, *b*, on the line long enough to depress the spring-bolt *p*, by coming in contact with the pin *p*, it will 10 be thrown onto the switch at that station, because the main wheels *N* will be thrown off the track and the wheels *O* will take to the switch-track.

15 At the point of each switch devices are provided for insuring perfect action, as follows: The point of the switch-track *C* is supported in proper position by a hanger, *d*, which may be a branch of the main hanger *D*. This 20 hanger *d* reaches over the track just high enough above to allow the car to pass under, and guides *d* *d*' are fixed to the overhanging part of the hanger *d*, to guide and steady the car as it passes, a roller, *m*, being placed on the 25 top of the upright *M* to act upon the guides. As the cars hang pendent from the track, they may sway and swing as they move along, but they should pass the switch without swaying, and these guides effect that result. Fig. 1 30 shows the form of these guides and their position clearly. The car being thus held steady, it is ready to drop unto the switch without fail if the lower wheels are unshipped. From the switch-track *C* the car runs onto the elevator-track *C'* and is stopped by the buffer *C*', and may then be lowered down to the counter. The elevator consists of a framework, *H*, *H*', &c., which is guided on vertical rods *G*, and is operated by a cord, *L*, running 35 over a pulley, *L*'. On the elevator, besides the car-receiver *C*', there is a car-shipping device, by which the cars are placed upon the main line *A*. This device is seen in Figs. 1, 2, 4, 5, 6, and 7. It consists of a tilting platform, *I*, which is pivoted at *h* on brackets *H*', which are attached to the elevator frame-work *H*, and a sliding frame, *J*, with hooks or horns *j* *j*' and fingers *J*' *J*'.

The construction and operation are as follows: The elevator being let down to the counter, the car is hung on the hooks *j* by its cross-arm *N*', its hooks being set at an incline, as seen in Fig. 7, so that the car will hang at the same incline as the track, so that the wheels 55 will meet the track fairly. The elevator is then drawn up until the car-wheels are about opposite the track, when the end of the elbow-lever *K* (which is arranged, as shown clearly in Fig. 6, to move the slide *J* when depressed) comes 60 in contact with a finger, *F*, which depresses the lever *K* and moves the slide *J* out over the track far enough to bring the car-wheels directly over it, the elevator having been pulled up far enough while depressing the lever *K* 65 to bring the car-wheels just above the track. The position of parts at this time is clearly

shown in Fig. 5. The elevator is then lowered; the car rests on the track; the fingers *J*' *J*' strike on the top of the car and tilt up the platform *I*; the car has started, and the slide *J*, by reason of the tilting, has moved back onto the platform, and the elevator is lowered and secured at the switch-track, so as to be ready to receive an incoming car. The finger *F*, which depresses the lever *K*, as above described, may be on a cross-bar, *F*', which is adjustable by screws *f* at the proper height on the guides *G*, as seen in Fig. 5, or it may be on the cross-bar having the line-hanger *E* thrown, as shown in Fig. 1. Wherever placed 75 it should be adjustable, so as to be adjusted at each station in accordance with the grade 80 of the line *A*.

What we claim as new is—

1. In a conveyer apparatus, substantially 85 as shown, the combination, with a continuous taut-wire track which passes curves or corners by angular bends; of a curved track formed of another piece of metal and adjusted with relation to the main wire, substantially as shown, 90 so as to form a continuous properly-curved track.

2. In a conveyer apparatus, substantially 95 as shown, the combination, with a continuous taut-wire track which passes curves or corners by angular bends and a separate curved track, of an iron forming a connection for said curved track upon said main track, through which the said main track is deflected downward, so as to allow the curved track to lie in the plane of 100 the main track, substantially as set forth.

3. In a conveyer apparatus, substantially 105 as shown, the combination, with the curved track *A*' and the main track *A*, of the connecting-iron (R or T) which connects both tracks 110 and deflects the main track below the end of the curved track, substantially as and for the purposes mentioned.

4. In a conveyer apparatus, substantially 110 as shown, a car having thereon a running-gear for running on the direct line of track, which is provided with means, substantially as shown, whereby the wheels thereof may be tripped or thrown out of operative position, for the purposes mentioned. 115

5. In a conveyer apparatus, substantially 120 as shown, the combination, with the main or direct track, of a switch-track, the point of which lies in a substantially vertical plane with said main track, and a car having two sets of wheels arranged one set above the other, substantially as and for the purposes mentioned.

6. In a conveyer apparatus, substantially 125 as shown, the combination, with a main or direct track and a switch or side track, the latter of which has its point lying in a substantially vertical plane with the said direct track, of a car having two sets of wheels arranged one set above the other, one of which sets is designed to traverse the main track, and 130 is so adjusted as to be thrown out of position for use, and the other set is designed for use up-

on the switch-track when the said main wheels have been thrown out of position for use.

7. In a conveyer apparatus, substantially as shown, the combination, with the tracks B 5 and C and finger b, of the main car-wheels N, cross-bar N', pivoted catch-bar P, spring-bolt p³, pin p⁵, spring p², and the wheels O.

8. In a conveyer apparatus, substantially as shown, the combination, with the tracks B 10 and C, arranged relatively, substantially as shown, and a car, substantially as described, of the hanger d and guides d' d', arranged as shown, and for the purposes mentioned.

9. In a conveyer apparatus, substantially as shown, the combination, with the side track, C, of the track C', attached to the elevator, substantially as and for the purposes shown.

10. In a conveyer apparatus, substantially as shown, the combination, with the elevator, 20 of a sliding platform or car-holder, J, and

means, substantially as shown, for sliding out said car-holder by the upward action of the elevator.

11. In a conveyer apparatus, substantially as shown, the combination, with the elevator, 25 of the sliding platform J, adapted to hold the car, the elbow-lever K, and finger F, for the purposes mentioned.

12. In a conveyer apparatus, substantially as shown, the combination, with the elevator, 30 of the tilting platform I and the sliding car-holder J, with hooks j and fingers J', for the purposes mentioned.

In testimony whereof we affix our signatures in presence of two witnesses.
